UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

WARP STOP MECHANISM FOR LOOMS.

Application filed December 29, 1921. Serial No. 525,705.

To all whom it may concern:

Be it known that I, EDWARD S. STIMPSON, a citizen of the United States, residing at Hopedale, in the county of Worcester and State of Massachusetts, have invented an Improvement in Warp Stop Mechanisms for Looms, of which the following description, in connection with the accompanying drawings, is a specification, like characters on the drawings representing like parts.

This invention relates to warp stop mechanisms for looms, whereby the loom is brought to rest when a warp thread becomes broken or too slack for weaving purposes.

The present warp stop motion is, in some respects, a further development of the warp stop motion shown and described in the pending application of Edward S. Stimpson, Serial Number 505,262, filed October 4, 1921, now Patent No. 1,409,425, dated Mar. 14, 1922, and has for one of its objects to render the warp stop motion more sensitive, thereby requiring less power to operate the feeler and its carrier in its feeling and idle stroke, and avoiding injury to the drop wire or drop wires. In some aspects this feature of the invention is more clearly manifested in a broad or wide loom, yet the sensitiveness and facility of movement of the feeler as contemplated by the present invention may be advantageously embodied in other warp stop motions.

Another feature of the warp stop mechanism consists in a drop wire aligning device which enables the drop wires to be brought into alignment for engagement by the drop wire guide with which the aligned drop wires are to be associated. This feature of the stop motion may be advantageously employed in any form of warp stop motion for bringing the drop wires of a row into alignment, but its utility and advantages are best manifested where the drop wires are provided with elongated slots or openings through which the drop wire guide extends. This character and construction of the warp stop mechanism while herein-after described, is not claimed in this application but forms the subject of a divisional application.

Where the warp stop motion is employed on a broad or wide loom, the length of the drop wire guides and the distance apart of

the side supports are liable to cause lack of stability of the fixed portions of the warp stop mechanism, and this same characteristic is true with respect to the feeler carrier and feeler where the span between the side members of the feeler carrier is of considerable extent. Another important feature of the present invention, therefore, consists in so strengthening and bracing the parts that notwithstanding the width of the loom, the fixed and movable parts of the warp stop motion will be rendered sufficiently rigid and unyielding to operate effectively to discharge their respective functions.

The above features of the invention and other novel combination of parts will herein after be described in connection with the accompanying drawings which illustrate one good, practical form of the invention.

In the drawings:—

Fig. 1 is a perspective view of the main portions of the warp stop mechanism embodying the present invention, but with some of the parts omitted for the sake of clearness;

Fig. 2 is a detail perspective showing the brace for the drop wire guides and warp supports and the connection of the brace to the truss frame connecting the side brackets of the stop motion;

Fig. 3 is a side view of the main portion of the stop mechanism, showing one form of means for operating the feeler;

Fig. 4 is a cross-sectional view of the main portions of the feeler mechanism showing the aligning device for aligning the drop wires; and

Fig. 5 is a view similar to that of Fig. 4, showing the aligning device being applied or removed.

As hereinbefore stated, the present invention is shown as embodied in substantially the same type of warp stop mechanism as shown and described in the patent of Stimpson, referred-to, and the various features of the invention will be described in this connection, although in some aspects of the invention they may be utilized with other forms or types of stop mechanisms.

The loom frame 1 has connected to each side thereof the brackets 2 having slotted portions 3 to which are adjustably secured

the side brackets or supports 4, which in the present instance are adjustably connected to the bracket 2 by means of the bolt 5 and slot 6.

5 The supports 4, one at each side of the loom, constitute the supporting elements for the drop wire guides 7 and the warp supporting rods or bars 8. The number of the drop wire guides and warp supporting 10 bars may be varied to suit conditions of use, but in the present instance four are shown.

Extending between the supports 4 is a truss frame which, in the present instance of 15 the invention, comprises the upper and lower rails 9 supported at intervals by spacing blocks 10. The end portions of the truss frame are connected to the supports 4 by means such as the bolts 11.

20 The supports 4 have lugs 12 against which the drop wire guides 7 are secured by means of the clips 13, substantially as in the prior patent to which reference has been made. The warp supports 8 have their ends sus- 25 tained in open bearings carried by the side brackets or supports 4.

Mounted in the bearings 14 carried by each of the supports 4 is the rock shaft 15 carrying the arms 16, the upper end por- 30 tions of which are slotted at 17 for engagement with the feeler carrier as will presently appear.

The rock shaft 15 has extending from it the arm 18 to which is connected the rod 19, 35 the lower end portion of which engages one end 20 of a follower 21 pivotally mounted at 22 on the loom frame. The follower 21 has a shoe 22 which rides upon the cam 23 mounted upon the under or cam

40 shaft 24, which may be the usual cam shaft of the loom which is carried by suitable bearings on each side of the loom, as indicated at 25. The rod 19 may be adjusted in length by means of the turnbuckle 26.

45 The action of the cam 23 upon the follower 21 causes the feeler to move in its non-detecting or idle stroke or to the left, Fig. 3, while the weight of the arm 27 and associated parts acts by gravity to move the feeler

50 in the opposite direction, or, in other words, impart to the feeler its detecting stroke, and owing to the anti-friction devices, which facilitate movement of the feeler, such gravity actuation of the feeler in its detecting 55 stroke may be made of such light force as not to injure a drop wire by which the feeler is arrested.

Secured to and extending from the rock shaft 15 is the arm 27, Figs. 1 and 3, to which 60 is connected the link 28 which acts through a train of mechanism, substantially as shown and described in the prior Stimpson patent and in the patent to Ambler, No. 885,130, dated Apr. 21, 1908, to control loom 65 stoppage. The train of mechanism which

acts in response to the movement of the arm 27 is well known, and as it forms no essential part of the present invention, further description thereof is unnecessary. The drop wires as shown, consist of the metal pieces 70 29 which may be stamped out of sheet metal or otherwise formed, and each one is provided with a guide slot 30 and an enlarged head 31, all of which in the present instance, face in the same direction. So far as the 75 broad aspects of the present invention are concerned, the drop wires 29 may be any of the various well known types, but in the present instance they are shown as of the "hairpin" form, that is, portions of the drop wires are open-slotted and have the legs 32 which are passed over the warp threads α and the upper portion of the legs 32 rests upon the warp threads to thereby support the drop wires during weaving. Drop wires 80 are sometimes provided with a separate opening or hole through which the warp threads are passed, and either type is susceptible of use in connection with the present invention. 85

As will be seen from Fig. 5, the drop wire guides 7 pass through the slots 30 of the drop wires, that is, each row of drop wires has passed through it a drop wire guide 7, and to align the drop wires for insertion of the drop wire guides, a drop wire aligning device is shown as formed of the aligning members 33 which extend between the end members 34. The aligning members 33 are conveniently located when used in connection with the hairpin type of drop wire to enter between the leg portions 32 of the drop wires for aligning the drop wires of the row for the insertion of the drop wire guide. 90

Each end member or saddle 34 has connected at its ends a hanger for supporting the aligning device in its drop-wire-aligning position. In the present instance one end of the saddles 34 has adjustably connected thereto by a bolt or thumb-screw 35, Fig. 4, 100 the hanger 36 having a hooked upper portion 37 which may conveniently be hung upon some convenient portion of the stationary part of the stop motion, but in the present instance is shown as being adapted 110 to engage the rock shaft 15, as more clearly indicated in Figs. 4 and 5.

The other end of the saddle 34 has adjustably connected thereto the hangers 38 which may be adjustably secured to the saddle 34 by a bolt or thumb-screw 39. Each of the hangers 36 and 38 is slotted longitudinally so that the position of the aligning bars 33 may be properly adjusted. 120

In the use of the drop wire aligning device, the hangers 36 and 38 are hung upon a stationary part of the warp stop motion and as shown in the present instance on the rock shaft 15 and the truss frame 9 when the end supports or brackets 4 and the parts are 130

- in the loom and preferably in operative position. Under these conditions the warp threads *a* pass over and rest upon the warp supporting bars 8 as indicated in Figs. 4 and 5. The drop wires 29 of the row are then placed upon the warp threads *a* by inserting the drop wires successively over its appropriate warp thread with the lower end or leg portion of the drop wire engaged with the 10 associated aligning bar 33, as illustrated in Fig. 4. The effect of this is that all the drop wires 29 of the row, which are hung upon the warp threads and would be liable to tilt into different positions, are held in 15 alignment with their slots 30 positioned for the endwise insertion of the associated drop wire guide 7, which may be moved endwise as indicated in Fig. 1 to pass through the aligned slots 30 of the drop wires.
- 20 After the drop wire guide 7 has been introduced and operatively associated with its line of drop wires, it is secured to the end supporting brackets 4 by the clips 13 or other appropriate means, and the drop wire aligning device may then be detached and removed from the loom.

It will be apparent that the assembly of the drop wires and drop wire guides is greatly facilitated by the drop wire aligning device, and especially is this the case when the drop wires are supported upon the warp threads which pass from the usual warp beam forwardly of the warp stop mechanism.

35 In some cases it is desirable to brace the drop wire guides and warp supports 7 and 8 respectively, between the side supports 4, and this is particularly advantageous in broad or wide looms. In the present instance this is accomplished by a centre brace 40, Fig. 1, which is secured to the truss frame 9 and has slots 41 in its upper edge which engage the drop wire guides 7 or through which the drop wire guides 7 may be passed as they are moved endwise through the drop wires. The centre brace 40 is also provided with a series of openings 45 between its upper and lower edges through which the warp supports 8 pass, the result being that the drop wire guides 7 and warp supports 8 between the side brackets 4 are stabilized and supported in a manner such that during the operation of the loom and the warp stop mechanism, the parts will be held in their operative position without flexing even in the wide loom.

40 It may sometimes be desirable, also, to further support the rock shaft 15 between its bearings; and to this end the brace 40 is provided with a supporting portion 42, Fig. 2, which supports the shaft 15 intermediate its ends.

When, owing to the wide character of the loom, the centre brace 40 is not sufficient to stabilize the parts and render them suffi-

ciently rigid, other bridges or braces 43 may be interposed between the centre brace 40 and the side brackets; and inasmuch as the drop wire guides 7 bear the thrust of the feeler when it engages a drop wire, the intermediate braces 43 are formed with slots or openings 44 in the upper edges thereof into which the drop wire guide 7 may fit. The openings 44, like the openings 41, are preferably made of less depth than the 70 depth of a drop wire guide 7, and the intermediate braces 43, like the centre brace 40, are secured as at 45 to the truss frame 9 which is preferably below the plane of the warp threads.

75 The feeler, which detects when a drop wire fails to be supported by its warp thread and thereby bring the loom to rest, consists of a feeler carrier between the side members of which, the feeler, or feelers as the case may be, extend. The ease of feeler movement and consequently its delicacy of action under the light actuating force, requires that the feeler be supported for detecting movement with as little resistance to 80 such movement as possible; and this is particularly important in broad or wide looms, though it may be of importance also in narrower looms. As shown in the present instance, the feeler carrier consists of members 46 between which extend the feelers 47, Figs. 1 and 3. The members 46 of the feeler carrier are each formed with an arm 48 through which extends a pin 49 for engagement with the slot 17 of the actuating 85 means, substantially as more fully described in the Stimpson patent to which reference 95 has been made.

95 Each of the side members is provided with a chamber 50 for an anti-friction device to be interposed between the side members of the feeler carrier and their support. In the present instance the anti-friction device consists of the balls 51 contained in each of the chambers 50 and held therein by 100 the cover plate 52 which may be secured to the side members by appropriate means such as the screws 53. The plate 52 on each side member is provided with openings 54 through which a portion of the balls 51 extends, the result being that when the feeler 105 is in its feeling position upon its supports 55, and connected with the actuator, the anti-friction devices will be interposed between the side members and the supports 110 115 and permit ready movement of the feeler carrier and feeler in its detecting movements without the exercise of an amount of force that would otherwise be necessary, and while anti-friction balls are shown as one 120 good form of anti-friction devices, the invention is not restricted thereto but contemplates the use of any character of anti-friction devices. Under these conditions it 125 will be readily seen that even though the 130

feeler carrier and feeler or feelers be of considerable weight, the amount of force for giving the feeler its detecting movement will be small, and thereby obviate the liability that would otherwise be present of injuring a drop wire which fails to be supported by its warp thread.

In the present instance of the invention, the non-detecting stroke of the feeler is imparted positively through the cam 23 and connections as hereinbefore described, while the detecting stroke of the feeler (that which causes the feeler to engage a drop wire when it is supported by the warp threads) is induced by gravity, the weight of the arm 27 and its connecting link 28 being sufficient for imparting detecting movement to the feeler under the conditions hereinbefore described. When, however, the feeler in its detecting movement meets a wire that has been drooped by its warp thread, the feeler carrier and feeler are more readily brought to rest owing to the small amount of force required to move the feeler by gravity in its detecting stroke; and the dropped wire is not injured.

The advantages of the anti-friction devices interposed between the feeler carrier and its support are peculiarly manifested where the loom is a wide or broad loom, which requires that the feeler carrier and feeler be of considerable weight; but of course the present invention is not to be restricted to use in wide looms, as advantages may flow from the anti-friction device even in the more narrow looms.

The side members 46 of the feeler carrier are connected by the feelers 47, but in some cases this alone would not impart sufficiently stable character to the feeler carrier as a whole. Consequently the present invention contemplates further uniting the side members 46 of the feeler by a truss frame 56, Fig. 1, formed, it may be, substantially similar to the truss frame 9 of the stationary portion of the warp stop mechanism. The truss frame 56 is connected at its end portions in the present instance by bolts 57 which are shown as passed through the end portion of the truss frame and through the angle member 58 of one of the feelers 47, see Figs. 4 and 5.

The unobstructed removal of the feeler carrier and feeler from operative relation with the drop wires has been fully and clearly described in the prior Stimpson patent to which reference has been made; and when so removed from operative relation with the drop wires the feeler carrier and feeler in the present instance may be conveniently hung upon supports 59 projecting from the loom arch 60, and within handy reach of the loom attendant.

It is sometimes desirable to brace the feelers intermediate the side members of the

feeler carrier, and in the present instance the truss frame 56 has secured thereto the feeler braces 61 which are disposed above the feelers. The braces 61 have the inclined slots 62, Fig. 1, which receive the upper edge portions of the inclined feelers 47. The braces 61 are particularly advantageous in the use of a feeler of this character for wide looms, though they may serve advantageous purposes, also, for looms of different width.

What is claimed is:—

1. In a warp stop motion for looms, the combination of a feeler carrier comprising side members, a feeler supported by the side members of the feeler carrier, a support at each side of the loom by which the feeler carrier is supported and on which it has sliding detection movement, rotatable anti-friction devices between the side members of the feeler carrier and the side supports on which the side members of the feeler carrier slide, and means for imparting to the feeler carrier reciprocating movements relative to the side supports.

2. In a warp stop motion for looms; the combination of a series of drop wires normally supported by the warp threads during weaving, a feeler carrier comprising side members and a feeler supported by the side members, a support at each side of the loom for supporting the side members of the feeler carrier for sliding movements thereon, rotatable anti-friction devices between the side supports and the side members of the feeler carrier, and an actuator for effecting sliding movement of the feeler carrier on the side supports towards and from the drop wires.

3. In a warp stop mechanism for looms, the combination of a feeler carrier comprising side members and a feeler mounted on the side members, side supports, one at each side of the loom, for supporting the side members of the feeler carrier for sliding movement thereon, rotatable anti-friction devices mounted upon the side members of the feeler carrier and supporting the feeler carrier on the side supports, and an actuator for imparting to the feeler carrier sliding movement relative to the side supports.

4. In a warp stop mechanism for looms, the combination of a feeler carrier, a feeler carried thereby, feeler carrier supports constructed and arranged to support the feeler carrier for unobstructed removal from said supports, anti-friction devices between the feeler carrier and the feeler carrier supports acting to make sensitive sliding movement of the feeler carrier relative to the supports, and an actuator for sliding the feeler carrier on said supports.

5. In a warp stop mechanism for looms, the combination of a series of drop wires normally supported by the warp threads during weaving, a feeler carrier, a feeler

- connected to the feeler carrier, side supports on which the feeler carrier slides, an actuator for imparting sliding movements to the feeler carrier to cause the feeler to approach and recede from the drop wires, and anti-friction devices for facilitating sliding movement of the feeler carrier on the side supports towards and from the drop wires. 5
6. In a warp stop mechanism for looms, 10 a feeler carrier comprising side members carrying rotatable anti-friction devices, supports on which the anti-friction devices travel back and forth, an actuator for traveling the feeler carrier on its supports, and a feeler extending between the side members 15 of the feeler carrier. 10
7. In a warp stop mechanism for looms, the combination of brackets at each side of the loom frame, a series of drop wires normally supported by the warp threads between the brackets during weaving, supports connected to the brackets, a feeler carrier 20 slidable on the supports and carrying a feeler, rotatable anti-friction devices between 25 the feeler carrier and the supports, and an actuator for moving the feeler carrier. 25
8. In a warp stop mechanism for looms, the combination of a series of drop wires, a feeler carrier comprising side members, supports 30 on which the feeler carrier is supported for sliding movement constructed and arranged to permit unobstructed removal of the feeler carrier, a truss frame extending between the side members of the feeler carrier, and connected to each of them to stabilize the carrier, and an actuator for imparting detecting movements to the feeler carrier. 35
9. In a warp stop mechanism for looms, 40 the combination of a series of drop wires normally supported by the warp threads during weaving, a drop wire guide, a feeler which is actuated in its non-detecting movement by power and in its detecting movement by gravity and adapted to be arrested in said detecting movement by a drop wire when it is released by a too slack or broken warp thread, and anti-friction devices between the feeler and its support which render the feeler responsive to light gravity 45 actuation in its detecting movement. 50
10. In a warp stop mechanism for looms, the combination of a series of drop wires normally supported by the warp threads 55 during weaving, supports at each side of the loom, a feeler carrier mounted for sliding movement towards and from the drop wire, a truss extending between and secured to each of said supports for rigidly connecting 60 them, and an actuator for sliding the feeler carrier on the supports. 60
11. In a warp stop mechanism for looms, the combination of a series of drop wires adapted to be supported by the warp threads 65 during weaving, a feeler having a detecting movement, a drop wire guide, supports at opposite sides of the loom for supporting the drop wire guide, a truss frame extending between the two supports transversely of the loom frame, and a brace between the supports and engaging the drop wire guide. 70
12. In a warp stop mechanism for looms, the combination of a series of drop wires, a drop wire guide, a feeler having a detecting movement which is arrested by engagement of a drop wire when it is released by a slack or broken warp thread, carriers for the feeler, and a truss frame extending between and connecting the carriers and movable therewith. 75
13. In a warp stop mechanism for looms, the combination of a feeler carrier comprising side members and a feeler carried thereby, said side members of the feeler carrier having rotatable anti-friction devices 80 mounted thereon, side supports for supporting the side members constructed and arranged to permit unobstructed removal of the feeler carrier and anti-friction devices therefrom, a series of drop wires normally supported by the warp threads during weaving, and an actuator for sliding the feeler carrier on the side supports. 85
14. A warp stop mechanism for looms, comprising, in combination, a series of drop wires normally supported by the warp threads during weaving, a drop wire guide for guiding the drop wires, a feeler having a detecting movement and adapted to be arrested in said movement by a drop wire 90 when it assumes an abnormal position due to a too slack or broken warp thread, an actuator for the feeler, a support for the feeler, and anti-friction devices between the feeler and its support which render the feeler responsive to a light actuating force tending to move it. 95
15. A warp stop mechanism for looms, comprising, in combination, a series of drop wires normally supported by the warp threads during weaving, a drop wire guide for guiding the drop wires, a feeler having a detecting movement and adapted to be arrested in said movement by a drop wire 100 when it assumes an abnormal position due to a too slack or broken warp thread, a support for the feeler, an actuator for the feeler, and anti-friction balls between the feeler and its support which render the feeler responsive to a light actuating force 105 tending to move it. 110
16. In a warp stop mechanism, the combination of a series of drop wires, a guide for the drop wires, a feeler, a support for the feeler and relative to which the feeler has detecting movement, rotatable anti-friction devices between the feeler and said support which render the feeler responsive to a light actuating force tending to move it, and an actuator for the feeler. 115
- 130

17. In a warp stop mechanism for looms, the combination of a series of drop wires, a drop wire guide, a feeler carrier comprising side members having recesses, anti-friction devices contained within the recesses of the side members and adapted to sustain the feeler carrier on its support, a feeler mount- ed on the feeler carrier, and an actuator for giving the feeler carrier and feeler move-
ment on the said support. In testimony whereof, I have signed my name to this specification.

10

EDWARD S. STIMPSON.
